ROBERT HENRY MARRIOTT, OF BROOKLYN, NEW YORK

POWER LIMITING DEVICE

Application filed July 7, 1928. Serial No. 291,092.

This invention relates to power limiting devices. Its object is to limit the power which may be transferred from a source to a subsequent circuit, that is, to insure that the power in excess of a predetermined amount shall be materially reduced in the transferring of power from the source to the subsequent circuit. This object is accomplished by making use of the fact that air and other gases are insulators at lower voltages, lose their insulating quality at higher voltages and regain their insulating quality when the applied voltage falls below a critical value. When the available power is great enough to provide a voltage and current sufficient to break down the insulating quality of a practicable thickness of air or other gas it is then practicable to utilize the above mentioned characteristic of air and other gases to shunt off and to neutralize excess power.

This invention applies more particularly to the audio frequency circuits of radio receiving systems in which sufficient amplified power is now commonly developed by undesired disturbances to alone or in addition to the desired broadcasted power produce voltages that will break down the insulating quality of practicable thicknesses of air or other gases.

As a practical illustration, lightning discharges cause clicks and crashes to be produced by the loud speaker of a radio broadcast receiver, that are very much louder than the maximum volume of the music which is being reproduced by the loud speaker. Such clicks and crashes when of short duration and when they are reduced in volume to that of the maximum volume of the music, interfere very much less than they do when they are several times as loud as the music.

The specific purpose of this invention is to provide a means for limiting the power delivered to the loud speaker to a power equal to the maximum satisfactory power obtainable from the particular broadcast that is being received. This makes it desirable that the power limiting device be adjustable for different strength of received broadcasts. Such adjustability can be accomplished by

varying the applied voltage, the length of the path through the gas or the gas pressure, or by combining two or more of these variables. Therefore, this application describes a power limiting device applicable for use in broadcast reception including means for varying the point of power limitation to conform to the variations of normal power available from broadcasting programs.

Fig. 1 is a schematic diagram of my invention.

Fig. 2 is a schematic wiring diagram of a modified form of my invention.

Fig. 3 is another schematic diagram of a modified form of my invention.

Fig. 4 is a detailed view of adjustable gap.

Fig. 5 illustrates a type of low pressure gas tube gap embodied in my invention.

Fig. 6 illustrates in modified form a low pressure type of gas tube gap embodied in my invention.

Fig. 7 illustrates in modified form a multiple electrode low pressure gas tube gap embodied in my invention.

Fig. 8 illustrates in modified form combination of a low pressure gas tube gap and open spark gap embodied in my invention.

My invention will be more clearly understood when the following description is read with reference to the several views in the accompanying drawings.

Reference will now be had to Fig. 1 in which, 1 represents the primary of an audio frequency transformer and 2 and 3 represent the split secondary of that transformer. The half of the secondary marked 2 is connected to the primary 4 of a second audio frequency transformer, the secondary 6 of which is connected to a loud speaker 7. The half of the secondary marked 3 is connected to 4 through the common connection of 2 and 3 and at its opposite end to one side of the adjustable discharge gap 5. The other side of this gap is connected to the upper end of the secondary winding 2. The secondary winding comprising equal parts 2 and 3 is a continuous winding such that with the adjustable gap closed to produce a short circuit, 2 and 3 are in opposition whereby the potential of 2 neutralizes the potential of 3 to such an extent that little

or no current flows through the primary 4. The ratio of the turns in the secondary 2 and 3 to the turns in the primary 1 is such that the stepped up potential is capable of jumping the gap 5 when the strength is above normal loud speaker volume. If the broadcast is not very loud and the clicks and crashes due to various forms of so-called "static" are louder, the adjustable gap is closed to a point a little too wide to allow voltages generated by the broadcast to jump the gap. The voltages generated by the static disturbances alone or added to the broadcast voltages, break down the gap and neutralize the potential across the primary 4 by an amount approximately equal to the amount the potential of secondary 2 has been raised by the static above the normal broadcast voltage. This reduces the effect of clicks and crashes so they are practically no louder than the broadcast. Large amplitude clicks of short duration may be thus reduced from distressing loudness to being of no particular consequence among musical notes of longer duration. The impedance of the primary winding 4 is made about equal to the impedance of one half of the split winding 2 and 3 or equal to 2 or 3.

Figure 2 is similar to Figure 1, except that 30 a variable resistance 8 is provided and the speaker 7 is substituted for the primary winding. By providing the variable resistance with the discharge gap connectible to points 10 or 11, finer adjustments of relative impedances are possible. By making the impedance of the winding of the loud speaker approximately equal to 2 it is not necessary to use a transformer as is shown at 4 and 6 in Figure 1.

40 In Figure 3 the discharge gap is not adjustable but the voltage impressed on the gap is made adjustable by making the secondary halves 2 and 3 variable as to the number of turns in use. In this case 4 may represent the primary of a transformer such as 4 and 6 in Figure 1 on the winding of a loud speaker; however, 4 is preferably adjustable as to number of turns in use so that the impedance of 4 may be made approximately 50 equal to the impedance of 2.

Figure 4 shows a simple form of an adjustable gap 5 the length of which is varied by operating the threaded portion 8 with the head 10 through the fixed support 9 to bring 55 the point nearer to or farther from the fixed point 6 supported by 14. The support 14 being connected to a terminal 12 and the support 9 being connected to a terminal 13, all parts being of conducting material except the base 11 and the screw head 10 which are of insulating material.

Figure 5 illustrates another form of variable discharge path comprising a series of low pressure gas tubes of a character similar to 65 Geisler tubes arranged to use one or two or

more in series. 6 represents the insulating and vacuum retaining wall of the tubes. 7 and 8 represent the electrodes and 5 represents the gaps between electrodes. The tubes "a", "b" and "c" are connected in series with the free electrode of the end tube "a" connected to a terminal 12. The connection between tube "a" and tube "b" is connected to a switch contact 9. The connection between the tube "b" and the tube "c" being connected to a switch terminal 10. The free electrode of the tube "c" is connected to a switch terminal 11. Switch arm 14 is connected to a terminal 13 and can be brought into contact with the switch terminals 9, 10 and 11. All three tubes may be adjusted to break down at the same voltage or by using different lengths of gaps or different gas pressure or both, or they may be adjusted to break down at different voltages.

Figure 6 shows a low pressure gas tube wherein the length of the gap may be adjusted by turning the tube. 6 is the envelope, 12 and 13 are terminals connected to electrodes 8 and 7 respectively. Electrode 7 is hinged at 1 so that if the tube is rotated 90° to the left about 1 the loose portion of electrode 7 will take the position shown in the dotted line, thereby widening the gap 5 for every position between the vertical and horizontal positions of the loose portion of 7. As the break down voltage varies with the length of the gap, this makes it possible to adjust the tube for different break down voltages.

Figure 7 shows a tube in which several electrodes 8 are sealed in at different distances from electrode 7 and connected to switch points 9, 10 and 11. Switch arm 14 is arranged to make contact with 9, 10 or 11 and is connected to terminal 13 while electrode 7 is connected to terminal 12.

In Figure 8 a low gas pressure tube is shown in series with an adjustable spark gap in normal air pressure. 6 is the envelope of the tube, 7 and 8 the electrodes and 5 the discharge gap. 17 is the fixed electrode of the gap, 18 is the adjustable electrode and 15 is the gap of an adjustable gap similar to that described in Figure 4. The ordinary gap in air produces a somewhat rougher sound in cutting off peaks than does the gap in reduced gas pressure while the gap in air is the more simple from the standpoint of adjustability. Using the two in series gives practically the range of adjustability of the gap in air and less roughness of sound than is produced by the gap in air alone. Also the permanent gap in gas prevents the short-circuiting of the discharge gap system.

I claim:

1. A power limiting device comprising a transformer having a primary and a pair of secondary windings, a spark gap adapted to be broken down by an excess potential, 130

- said spark gap when broken down permitting a flow of current in one of said secondary windings in opposition to the flow of current in the other winding, and means to adjust 5 said spark gap to a predetermined potential.
2. A power limiting device comprising a transformer having a primary and a pair of secondary windings, a spark gap adapted to be broken down by an excess potential, said
- 10 spark gap when broken down permitting a flow of current in one of said secondary windings in opposition to the flow of current in the other winding, said spark gap comprising a gas tube in which the distance between the
- 15 electrodes may be varied by revolving the tube.
3. A power limiting device comprising a transformer having an input primary winding and an output secondary winding magnetically coupled thereto, a low pressure gas
- 20 tube capable of passing a current when a given potential is exceeded, said tube having its electrodes connected respectively to one end of and the middle of said secondary winding.
- 25 4. In a radio receiving system, an audio frequency transformer having a primary winding and a split secondary winding, a second audio frequency transformer, one end of the primary of which is connected to said
- 30 secondary by a conductor having uniform conductivity, and the same end of said primary of said second transformer being connected to the opposite end of said secondary of the first mentioned transformer by a shunt
- 35 containing an adjustable spark gap and the opposite end of said primary being connected to the midpoint of said secondary of said first mentioned transformer.
- 40 5. A power limiting device comprising a transformer having a primary winding and two opposed secondary windings, one of said secondary windings being connected at all times in current conducting relation to output terminals and the other of said windings
- 45 being connected to the same output terminals by a circuit containing a spark gap, said spark gap preventing flow of current through said second winding before a predetermined potential is exceeded.
- 50 6. A power limiting device comprising a transformer having a primary winding, and a continuous secondary winding, an output conductor connected to a midpoint of said
- 55 secondary winding to split the same into two equal parts, one end of said secondary winding being connected to one side of the input circuit of a translating device, the other end of said secondary winding being connected
- 60 through a spark gap to the same side of the input circuit of said translating device, and said midpoint conductor being connected to the other side of the input circuit of said translating device, whereby said secondary is
- 65 split into two portions opposing each other
- when current flows through said spark gap. Signed at New York, in the county of New York and State of New York, this twenty-sixth day of June, A. D. 1928.
